UNITED STATES PATENT OFFICE

2,434,732

EXTENSIBLE DRILL PRESS

James Alick, New York, N. Y.

Application June 30, 1944, Serial No. 544,022

2 Claims. (Cl. 77—27)

1

This invention relates to drill-presses, and more particularly to the kind which have an extensible drill-head, the latter being secured upon the drill frame in such a manner as to allow the extension of the drill-chuck to various positions facilitating the drilling of holes in castings and other articles without necessitating the moving of the work from its original position upon the drill table.

The main object of this invention is, therefore, to provide a drill-press which, differentiating from drill presses already in use, will be equipped with a drill-head that is attached to the drill frame of the press in such a manner as to allow for substantial adjustment towards or away from the said drill frame. In standard drill-presses utilized at present in shops and factories, when a casting or other piece of work has to be drilled, the centers of the holes are laid out before-hand upon the work by the mechanic or draftsman. Once the centers of the holes to be drilled are located, they are marked by means of a center punch, and the work is placed upon the table of the drill-press to drill the holes. With the drill-press of the present invention, such preliminary marking can be dispensed with, as all that is required is to mark the center of the first hole to be drilled, and then by simply following the dimensions and remarks of a drawing or blueprint, the operator can adjust the head of the drill in any position and angle required, and proceed to drill the holes by just watching the scale that is etched upon the extensible horizontal drill-head supports, and the angle of degrees upon the rotating members of the drill-press. Thus the time for marking all the various holes to be drilled is saved, and the work does not have to be touched from the time it is secured to the drill table until all the holes have been drilled. This is an important feature when the casting or work to be drilled is too heavy to be moved or too hard to be secured in different positions upon the table of the drill-press.

A further object of this invention is to provide a drill-press which will have an extensible drill-head.

Another object of this invention is to provide means facilitating the extension of said drill-head away from or towards the drill frame of the press.

Still another object of this invention is to provide a drill-press and means thereon for extending the drill-head away from or towards the frame of the press, dispensing with the changing of the position of the work upon the drill table.

2

Still another object of this invention is to provide a drill-press having an extensible drill-head and means for extending or retracting said drill-head towards or away from the drill frame, facilitating the drilling of various holes in a work without changing the position of said work upon the drill table of the press.

An additional object of this invention is to provide a hand wheel and gear and rack means thereon to facilitate the extension or retraction of said adjustable drill-head towards or away from the frame of the drill-press.

A still further object of this invention is to provide means for rotating the drill-head circumferentially around the frame of the drill-press, and scale means thereon for regulating the degree of rotation around the frame of the drill-press.

Still another object of this invention is to provide an extensible drill-head and adjustable means for adjusting said drill-head away from or towards the frame of the drill-press, and scale means thereon for regulating the distance between the adjustable drill-head and the frame of the machine.

Other objects and advantages of this invention will hereinafter appear as the description of this invention will proceed.

Referring to figures:

30 Fig. 1 is a perspective view of the drill-press showing the extensible drill-head, the handle for extending or retracting said drill-head away from or towards the frame of the machine, and the manner in which the retractable head is supported upon the extending rods which are secured to the motor operating the drill chuck shaft.

Fig. 2 is a side view of the drill-press showing the retractable drill-head and other parts of the press, as also the scale etched upon the rods supporting the head to the frame of the press.

Fig. 3 is a section taken on the line 3—3 of Fig. 2, showing the manner the extensible rods are attached to the head of the press and to the casting supporting the motor.

45 Fig. 4 is a section taken on the line 4—4 of Fig. 2, showing the manner the extensible rods are located within the supporting frame of the drill-press and the way the rods are retracted by means of gears and gear racks and through the use of a manually operated wheel.

Fig. 5 is a section taken on the line 5—5 of Fig. 4, showing the manner the extensible rods are located within the supporting casting, and the manner the operating spur gears are in mesh with the rack operating the extensible rods.

Fig. 6 is a sketch showing the manner in which a piece of work is drilled upon the drill-press of the present invention, first, by drilling one hole, and from there on, by means of the scale etched upon the extensible rods and the marking of degrees upon the supporting head; other holes can be drilled without removing the work from the drill plate, or changing its position upon it.

Referring to Fig. 1, numeral 20 designates the frame of the drill-press proper which consists of a column 21, a base 22, and an adjustable table 23. The table 23 can be moved vertically upon the column 21 by loosening the table clamp 24, while the adjustable drill-head 25 can be moved horizontally by means of a pair of slideable bars 26 and 27 which are slideably attached to the drill support 28.

One end 29 and 30 of the slideable bars 26 and 27 is rigidly attached to the bushings 30a and 31 of the drill-head 25, while the opposite ends 32 and 33 of the slideable bars 26 and 27 are attached to bushings 34 and 35 of the motor plate 36. The motor 37 is attached by means of screws 38 to the plate 36 and has a three stage pulley 39 which drives the chuck shaft 40 by means of a secondary V-pulley 41 and a V-belt 42.

The drill-head 25 has a regulation feed lever 43, a depth stop 44, and a quill lock 45. A guard 46 is located above and over the V-pulley 41 to protect the operator when operating the machine.

The slideable bars 26 and 27 are equipped at the lower part thereof with a gear rack 47 and 48 which is attached to the bars 26 and 27 by means of screws, rivets or welding. A pair of spur gears 49 and 50 is in mesh with the gear racks 47 and 48 while being keyed to a shaft 51 which is rotated by a four handled wheel 52. The shaft 51, at its extreme left end, has a threaded extension 53 and a tightening nut 54 which is manually tightened by the handle 55. Another tightening nut 56 is secured at the upper portion 28a of the supporting frame 28, and has a handle 57. The tightening nut 56 is used to secure the drill support 28 to the column 21 to prevent the former from rotating or wobbling.

Operation

The operation of the drill-press shown and described in Figs. 1 to 6 inclusive is similar to the operation of standard drill-presses, but differentiating in the manner in which the holes in the work on the drill table are drilled. While in standard drill-presses the work upon the drill table has to be moved under the center of the drill for every hole that must be drilled, in the drill-press described in this specification, the work upon the drill table remains stationary, while the drill chuck supporting the drill is moved.

For this purpose, the chuck frame 25 is secured to a pair of extensible rods 26 and 27, which are secured to the shaft frame and are made to slide within openings located upon a drill frame 28 which is attached to the column 21 supporting the drill proper. The rods 26 and 27 also support a motor plate 36 which carries the electric motor 37. It can be seen from Figs. 1 and 2 that the drill shaft 40 is operated from the motor 37 by means of a pair of V-pulleys 39 and 41 and a V-belt 42. It can be also seen that as the rods 26 and 27 are moved, the motor and the drill frame are taken along so that the drill is continuously operated even while extending

or retracting the chuck frame 25 from or towards the drill frame 28.

Referring to Fig. 2, the rods 26 and 27 are equipped with gear racks 47 and 48 which mesh with the spur gears 49 and 50. The spur gears 49 and 50 are keyed to a shaft 51 which is manipulated by the operator of the drill-press by means of a four-armed handle 52 whenever it is required to extend or to retract the rods 26 and 27. To facilitate the clamping of the extensible rods in any chosen position, the shaft 51 is equipped with a clamp 54 which is threaded upon an extension 53. By turning the clamp 54 by means of the handle 55 one way or the other, the shaft 51 is made fast to the drill frame 28, or it is loosened up to allow its rotation.

To facilitate the rotation of the extensible chuck frame 25 in an arc around the drill frame 28, the latter is rotatably attached to the column 21 supporting the drill press proper. A clamp 56 operated by means of a handle 57 serves the purpose of disconnecting the drill frame 28 from the column 21 to allow its rotation.

To illustrate the manner in which this new drill-press is operated, if a number of holes has to be drilled in casting (W), as it is shown in Fig. 6, the extensible drill-chuck 25 is at first set to drill the hole (I). After drilling the hole (I), the second hole (II) is drilled by swinging the extensible chuck frame 25, 40 degrees to the left, as shown on the drawing, and in accordance with the scale (not shown) for angular movement which is etched upon the sleeve 61. Then, by securing the drill frame 28 in position, the operator turns upon the handle 52, and at the same time watching the inch scale (S) which is etched upon the rod 26 until the right amount of inches (B) is read. Subsequently, the chuck frame 25 is locked in position by means of the clamp 54 operated by the arm 55, and then, the operator proceeds to drill the hole (II).

In a similar manner, the hole (III) is drilled by swinging the drill chuck 25 this time 45 degrees to the right, and by extending the same at an amount of (C) inches from the hole (I). Finally, the fourth hole (IV) is drilled by returning the chuck frame 25 to zero position and by extending the same an amount of (E) inches from the first hole (I). In a similar manner, the other holes can be drilled in the casting (W) without necessitating the changing of position of the casting upon the drill table.

From the foregoing description of the construction and operation of the drill-press shown in Figs. 1 to 6 inclusive, it can be seen that it is well adapted for drilling holes without necessitating the changing of the position of the article to be drilled upon the drill table. The drill-press here described is simply constructed and conveniently operated, and although it is obvious that it is susceptible to some changes and modifications, they are possible without departing from the principles and the spirit thereof, and for this reason I do not wish to limit myself to the exact and precise arrangement and formation of the several parts herein shown, in carrying out my invention in practice, except as claimed.

Having now described my invention, what I claim is:

1. In an extensible drill-press of the class described including an upright support, a drill table held upon said support, the upper portion of said support including a drill-chuck holder having a horizontally slideable drill-chuck frame, a vertical drill-shaft rotatably mounted in said drill-

chuck frame, said shaft being provided with a drill clamp and a drill and being rotated by means of a belt-pulley secured thereto, and means for sliding said drill-chuck to facilitate adjustment of said drill with locations for holes to be drilled in work secured to said table; said slideable means comprising a pair of extensible rods, one end of said rods being secured to said drill-chuck, the other end of said rods being secured to a motor support member, said rods being slideably held within holes in said drill-chuck holder, and gear means included for sliding said bars or rods in said support, said gear means comprising a pair of gear racks held to said rods and being in mesh with a pair of spur gears held to a common shaft and being manually rotated by means of a handle, the motor support member having a motor including a pulley, said motor rotating said pulley upon said drill-shaft by means of a belt, said drill-chuck support being slideably held upon said upright support.

2. The same structure as set in claim 1, and

a collar being held upon said upright support and below said drill-chuck holder, said collar having a clamp and a handle operating said clamp, the release of said clamping action upon said collar allowing the drill-chuck holder to be lifted or lowered upon the upright support aforesaid.
